UNITED STATES PATENT OFFICE.

WILLIAM H. ZORGER, OF CHAMPAIGN, ILLINOIS.

REFLECTOR FOR HEADLIGHTS FOR VEHICLES.

Application filed February 9, 1925. Serial No. 7,997.

The present invention relates to improvements in reflectors for headlights for vehicles being particularly intended for use with automobile headlights. The primary object 5 of the invention is to provide a reflector which will permit of positioning the headlight on a substantially vertical standard and provide for a maximum illumination of the roadway in advance of the vehicle without 10 producing objectionable glare.

With this and other objects in view, the invention resides in the construction and arrangement of parts that will be hereinafter more particularly pointed out and described 15 in connection with the accompanying drawings.

In the drawings:—

Figure 1 is a vertical sectional view of a headlight reflector embodying the present 20 invention.

Figure 2 is a face view of the improved reflector.

Figure 3 is a sectional view, substantially on the line 3—3 of Figure 2.

Figure 4 is a sectional view, substantially 25 on the line 4—4 of Figure 2.

Figure 5 is a view similar to Figure 1 illustrating a slightly modified form of the improved reflector.

Figure 6 is a similar view of another embodiment.

Figure 7 is a side elevation of another form of the same type as that of Figure 1.

It will be understood, of course, that much 35 of the illustration of the invention is more or less diagrammatic and there can be considerable modification of details without departing from the invention. The drawings are intended to be illustrative rather than 40 restrictive, and except where details are specifically referred to in the accompanying claims, the invention is not intended to be limited to the exact structures shown in the drawings.

45 In the drawings the invention is illustrated in connection with a reflector corresponding to an ordinary paraboloidal reflector of one and a quarter inch focal length, and the source of light is represented as being a V-shaped filament one-eighth inch in length arranged horizontally. With such a light source and reflector it is found when 50 the edge of the reflector is in a vertical plane that the rays reflected from the central zone

A, having a width of approximately one 55 inch, will not rise above the horizontal more than one quarter of an inch per foot or six inches in a distance of twenty-five feet. Similarly the rays of light reflected from the annular marginal zone B, having a width of 60 approximately three quarters of an inch will only rise above the horizontal at the rate of about one quarter of an inch per foot or a total of six inches in a distance of twenty-five feet. The intermediate zones C, D, 65 however, will produce reflected rays which make a considerably greater angle with the horizontal, commonly as much as one-half inch per foot.

In order to prevent objectionable glaring 70 from a headlight provided with an ordinary paraboloidal reflector, therefore, it is necessary to support the headlight on an inclined standard or in an inclined position. The inclination must, of course, be sufficient to 75 prevent the rays reflected from the intermediate zones C, D, rising above the horizontal at suitable distances and this, of course, results in throwing down rays from the zones A, B, which in themselves do not 80 have an objectionable rise.

By thus tilting the headlight the distance at which the reflected rays particularly those from the zones A, B, are effective is greatly reduced.

According to the present invention, means 85 are provided whereby the rays reflected from the intermediate zones C, D, will be projected at an angle to the horizontal substantially the same as those reflected from the 90 central zone A and marginal zone B. Therefore, the headlight may be supported on a substantially vertical standard, or one but slightly inclined and the rays reflected from the zones A, B, rendered useful for the 95 maximum distance.

That is, by the present invention the zones C, D, are arranged out of the portions of the normal parabolic sections connecting the central and marginal zones A, B, of an ordinary paraboloidal reflector and at such an angle to said central and marginal zones that the rays of light reflected therefrom will, for example, be caused to rise above the horizontal approximately one quarter of an inch per foot instead of one-half inch per foot. This enables the rays from the central and marginal zones to be utilized for illuminat- 100 105

ing the roadway at a considerable distance in advance of the vehicle, while the rays reflected from the intermediate zones will thoroughly light the road in the immediate vicinity of the vehicle.

As the rays of light reflected from the intermediate zones C, D, are not primarily intended for distance illumination, it is important that the rays reflected from these zones be deflected or dispersed laterally to a considerable degree so that there may be a maximum amount of illumination of the roadway immediately in front of the vehicle.

To accomplish this the faces of said intermediate zones C, D, are preferably fluted as shown in Figures 3, 4 and 5. The flutings S are preferably of the particular form illustrated, the ridge-like portions of those on the upper intermediate zone member C preferably increasing gradually in width from their upper to their lower ends while those on the lower intermediate zone D are of reverse form. This arrangement of flutings provides for a more rapid spreading of the rays reflected from the upper portion of the upper intermediate zone and the lower portion of the lower intermediate zone than from the other portion of such zones so that the beam of light thrown upon the roadway will be of substantially rectangular form.

Further, the flutings will be so shaped that the lateral dispersion effected by them will gradually decrease from the central rib or ridge to the shorter side members.

The intermediate zones C, D, can be formed separate from the central and marginal zones A, B, and means are provided, whereby said intermediate zones may be bodily adjusted relative to the marginal and central zones so that the operator may vary the relation of these parts in case it is desired to increase the distance to which the rays reflected by said intermediate zones will be projected.

In the embodiment of the invention illustrated in Figure 1 the sections E, F, of the reflector, the inner faces of which constitute the intermediate zones C, D, are connected to the section which forms the marginal normal parabolic zone B by hinges G. A lug H on each section E, F, is engaged by a thumb screw I mounted on a lug projecting from the section of the reflector whose inner face forms the central zone A. By turning the screws I it will be seen that the sections E, F, and the intermediate reflecting zones C, D, can be positioned in various angular relations to the central zone A and marginal zone B.

Guiding means L, M, (see Figure 7) may be arranged on the movable and relatively stationary sections of the reflector if desired.

Instead of making the upper and lower in-

termediate zones separately adjustable as above described, these may be formed of a single piece, as shown in Figure 6 and mounted to rock about a horizontal axis N positioned back of the normal parabolic central section A. This figure illustrates diagrammatically a solenoid O, mounted on the portion of the reflector whose inner face constitutes the annular marginal zone B and the core of which is connected to the reflector section P, the face of which includes the upper and lower intermediate reflector zones C, D. It is intended that the circuit including the solenoid O shall be provided with control devices located on the instrument board of an automobile for example, so that the operator may readily adjust the intermediate reflector zones into the desired relation with the central and marginal zones.

While it is possible to make the intermediate zones of the reflector adjustable relative to the central and marginal zones, the principal advantages of the invention can be attained by a construction in which all of the zones are formed integral, that is, by stamping a single sheet of metal. Such an arrangement is shown in Figure 5, in which it will be seen that the upper intermediate zone is rearward of the position of the normal parabolic section connecting the central and marginal zones of an ordinary paraboloidal reflector and the lower intermediate zone is in advance of the position of such normal connecting parabolic section.

Referring particularly to Figures 1 and 6, it will be seen that the edges of the intermediate sections E, F, are not offset uniformly to the adjacent edges of the central and marginal sections A, B. In the embodiments of the invention illustrated in these figures, the extent to which the edges of such intermediate zones adjacent the annular marginal zone are offset from such marginal zone will be less than the amount to which the other edges of such intermediate zones are offset from the plane of the central zone A. In the form shown in Figure 5 the upper zone E is uniformly back of the position of the normal parabolic section connecting the central and marginal planes and the lower zone F is uniformly in advance of the position of said normal parabolic connecting section.

It is believed that the advantages of the invention will be appreciated from the foregoing description and the drawings. It will be seen that the improved reflector enables the headlights to be positioned so that the maximum amount of light projected from the central and marginal zones may be utilized and avoids the production of undesirable glare from the rays reflected by the intermediate zones. With a headlight provided with the improved reflector and in

which the center of the lamp is at a distance of thirty-six inches above the road bed, it is only necessary to give a very slight inclination to the lamp. If the parts are positioned 5 so that none of the rays reflected from the marginal zone B will rise above the horizontal plane the center of the cone of light projected from said zone will impinge upon the roadway at a distance of one hundred and fifty feet from the headlight, while the centers of the light cone projected from the intermediate zones will contact with the road bed at a distance of seventy-five feet, thus 10 very effectively illuminating the road immediately in advance of the vehicle.

When the headlights are provided with ordinary paraboloidal reflectors, the lamp body must be positioned at a very considerable inclination to prevent the rays from the intermediate zones producing undesirable glare. The amount of the inclination thus necessary materially shortens the distance at 20 which the light rays from the central and marginal zones will contact with the roadway and thus reduces the effectiveness of the headlight.

It will be seen that in effect the improved reflector comprises two portions which are segregated, one from the other, namely, the 30 portion including the central transverse zone and the annular marginal zone, the rays reflected from which will not rise above the horizontal at an angle any greater than one quarter of an inch per foot; and the other 35 including the intermediate zones E, F, which would normally reflect rays at an angle to the horizontal exceeding one quarter of an inch per foot, but which are so related to the central horizontal and marginal zones that 40 the angle of rays reflected therefrom need not exceed that of those reflected from the horizontal and marginal zones so that a very slight tilt of the headlight, if any, will prevent any reflected rays from rising substantially 45 above the horizontal.

By the improvements two distinct light zones are produced and the axial rays from the border and central zone of a reflector set at an angle corresponding to six inches in 50 twenty-five feet will strike the roadway at a distance of one hundred and fifty feet in advance of a headlight, the focal center of whose reflector is thirty-six inches above the road level, while the axial rays from the 55 areas E, F, of such headlight will impinge upon the roadway at a distance of seventy-five feet in advance of the light.

Having thus described the invention, what is claimed is:—

60 1. A reflector for vehicle headlights having a transverse central zone and an annular marginal zone, the face contours of which are substantially the same as those of the corresponding zones of a paraboloidal reflector, two intermediate zones arranged in such

angular relation to said central and marginal zones that rays of light reflected therefrom will not rise above the horizontal to any greater extent than rays reflected from the central and marginal zones, and means on 70 the upper intermediate zone for dispersing laterally rays of light reflected therefrom.

2. A reflector for vehicle headlights having a transverse central zone and an annular marginal zone, the face contours of which are substantially the same as those of the corresponding zones of a paraboloidal reflector, two intermediate zones arranged in such angular relation to said central and marginal zones that rays of light reflected therefrom 75 will not rise above the horizontal to any greater extent than rays reflected from the central and marginal zones, and means on both said zones for dispersing laterally the 80 rays of light reflected therefrom.

3. A reflector for vehicle headlights having a transverse central zone and an annular marginal zone, the face contours of which are substantially the same as those of the corresponding zones of a paraboloidal reflector, and two intermediate zones arranged 85 in such angular relation to said central and marginal zones that rays of light reflected therefrom will not rise above the horizontal to any greater extent than rays reflected from the central and marginal zones, the reflecting face of the upper intermediate zone being provided with vertically extending flutings, the rib sections of which gradually decrease in width from the upper to the lower edge of the zone, and the reflecting face of the lower intermediate zone being provided with vertically extending flutings, the rib sections of which gradually increase 90 in width from the upper to the lower edge 95 of the zone.

4. A reflector for vehicle headlights having a transverse central zone and an annular marginal zone, the face contours of which are the same as those of the corresponding 100 zones of a paraboloidal reflector, and two intermediate zones arranged in such angular relation to said central and marginal zones that rays of light reflected therefrom will not rise above the horizontal to any greater 105 extent than rays reflected from the central and marginal zones, the reflecting faces of the intermediate zones being provided with means for spreading reflected rays laterally 110 which gradually decrease in power toward 115 the central zone.

5. A reflector for vehicle headlights having a transverse central zone and an annular marginal zone, the face contours of which are substantially the same as those of the corresponding zones of a paraboloidal reflector, two intermediate zones formed integral with each other and supported to rock about a horizontal axis positioned back of 120 the central zone, the upper intermediate zone 125 130

lying back of the position of the normal parabolic connecting section between the central and marginal zones, and the lower intermediate zone lying forward of the position of the normal parabolic connecting section between the marginal and central zones, and means for rocking said intermediate zones about their axis.

6. A reflector for vehicle headlights having a transverse central zone and an annular marginal zone, the face contours of which are substantially the same as those of the corresponding zones of a paraboloidal reflector, and two intermediate zones the face contours of which are out of the position of the normal parabolic sections connecting the central and marginal zones, whereby rays of light reflected from said intermediate zones will not subtend any greater angle to the horizontal axis of the reflector than rays reflected from the central and marginal zones.

7. A reflector for vehicle headlights having a transverse central zone and an annular marginal zone, the face contours of which are substantially the same as those of the corresponding zones of a paraboloidal reflector, and two intermediate zones bodily adjustable relative to said central and marginal zones and having their contours out of the positions of the normal parabolic sec-

tions connecting the central and marginal zones.

8. A reflector for vehicle headlights having a transverse central zone and an annular marginal zone, the face contours of which are substantially the same as those of the corresponding zones of a paraboloidal reflector, a zone intermediate the marginal and central zones, and above the latter, having its face contour out of the position of the normal parabolic section connecting the central and marginal zones, and means for adjusting said intermediate zone about a horizontal axis, for the purpose described.

9. A reflector for vehicle headlights having a transverse central zone and an annular marginal zone, the face contours of which are substantially the same as those of the corresponding zones of a paraboloidal reflector, and two intermediate zones bodily adjustable relative to said central and marginal zones and having their face contours out of the positions of the normal parabolic sections connecting the central and marginal zones, and means for simultaneously adjusting said intermediate zones, for the purpose described.

In testimony whereof I have hereunto set my hand.

WILLIAM H. ZORGER.
